UNITED STATES PATENT OFFICE.

COSAM TALLEYRAND BARTLETT, OF WARSAW, NEW YORK.

TANK-HOOP.

SPECIFICATION forming part of Letters Patent No. 417,381, dated December 17, 1889.

Application filed November 26, 1886. Serial No. 219,976. (No model.)

To all whom it may concern:

Be it known that I, COSAM TALLEYRAND BARTLETT, residing at Warsaw, in the county of Wyoming and State of New York, have invented certain new and useful Improvements in Tank-Hoops, of which the following is a specification, reference being had therein to the accompanying drawings.

This invention relates to hoops for large tanks, especially such tanks as are used for storing brine.

The object of the invention is to produce a tank-hoop which shall be cheap and of convenient application and which shall be durable.

Heretofore hoops for brine-tanks (which are generally composed of wooden staves) have generally been made of flat or band iron, the meeting ends of the band being riveted or welded together, and the hoop was placed over the top of the tank and driven down to tighten the staves. A flat hoop applied in this way is generally strained most at the lower edge, toward the large end of the tank. As the tanks are often twenty feet or more in diameter, it is difficult to apply such a hoop. As a very large surface of such a hoop is exposed to the corrosive action of the brine, the hoop soon rusts away and must be frequently renewed. Tanks hooped with flat hoops often burst, causing loss and damage.

Instead of using a flat hoop, I use a hoop made of round, oval, or similar rods, so that a convex surface of said rods shall bear on the staves; and I connect the ends of the rods forming the hoop or hoop-sections by a peculiar coupling, which I will now describe.

Referring to the drawings, Figure 1 represents a partial horizontal section of a tank with my hoop and coupling applied. Fig. 2 is a plan of the coupling-bar, showing one end of the hoop in dotted lines. Fig. 3 is a perspective of the coupling-bar. Figs. 4, 5, and 6 are cross-sections of the coupling-bar, Fig. 5^a showing a modification. Fig. 7 is a horizontal section of the staves of a tank, showing a hoop of three sections applied. Fig. 8 is a plan of a modified coupling-bar.

The letter A indicates the staves of the tank, which tank may be cylindrical or tapering.

B indicates a hoop or hoop-section, preferably a round metallic rod about one inch in diameter for large tanks. Oval or similar rods may be used; but I have found round rods to answer to best advantage. One end 55 of each rod may be headed down, or both ends may have screw-threads and nuts applied.

C indicates the coupling-bar, which is of malleable cast or wrought iron, of crescent form, the inner face of the bar of such curve 60 as to conform to the surface of the tank, the outer face of the bar having at least one lug D, through which the rods B pass, said lug having perforations for that purpose. The bar C also has two small bosses E, which are 65 either notched or perforated for the passage of rods B. The bar C may have two lugs D, as in Fig. 8, one end of a rod B passing through each and tightened, as shown.

The hoop is applied to the tank as shown 70 in Figs. 1 and 7, the latter figure indicating a hoop in three sections. The bar C is held tightly against the staves so far as it extends, and as the ends of the bar are thin the rod passes firmly against the staves between 75 these coupling-bars. The lugs E cause the coupling-bar to assume a horizontal position against the staves. The round bar B bears against the hoops more uniformly than a flat band, and, as has been stated, is much more 80 durable than a flat band. The lugs E and the rods B serve to support each other, and the hoop can readily be tightened by turning up the nuts. The face of the lug D is preferably beveled, so that the nuts will have a 85 fair bearing. While the ends of the rods are far enough removed from the tank to give freedom of movement in turning the nuts, the body of the bar C will firmly bear against the staves against which it rests, so that all the 90 staves will be supported by the hoop.

I claim—

1. In a tank-hoop, a coupler in crescent form having a boss projecting from its face and provided with two openings, a rounded rod 95 or rods separate from the coupler, detachably seated in said openings, and forming the main part of the hoop, said rod extending around the staves and through the openings in the boss and bearing on the horns of the crescent- 100

shaped coupler, and a nut on one end of said rod bearing against the boss, all combined substantially as described.

2. A tank-hoop consisting of rounded bars provided with nuts and a coupling-bar of crescent form to fit the staves, said bar having on its convex face a perforated boss D, through which the rods pass, and also having

supporting or guide lugs E, all in combination, substantially as described.

In testimony whereof I affix my signature in presence of two witnesses.

C. TALLEYRAND BARTLETT.
